UNITED STATES PATENT OFFICE.

HARVEY M. OWENS, OF LEOMINSTER, MASSACHUSETTS.

MOUNTING FOR HAIR-PINS AND THE LIKE.

1,273,530.

Specification of Letters Patent.

Patented July 23, 1918.

Application filed October 22, 1917. Serial No. 197,815.

To all whom it may concern:

Be it known that I, HARVEY M. OWENS, a citizen of the United States, residing at Leominster, in the county of Worcester and 5 State of Massachusetts, have invented new and useful Mountings for Hair-Pins and the like, of which the following is a specification.

This invention relates to a mounting, 10 preferably in the form of a card of pasteboard or the like, for hair-pins or other two pronged articles, and is particularly useful in connection with the mounting of celluloid hair-pins.

15 The principal objects of this invention are to provide an arrangement in which the pins can be applied with great rapidity by those who are skilled, and especially to provide a construction which will effectively 20 and surely hold the pins on the card and not allow them to be shaken off after they are once applied. Further objects of the invention are to provide an arrangement which will not bend the card or be likely 25 to mutilate it when the pins are being applied to it, one in which a relatively large number of pins can be applied in a small space, and one which is capable of use for a double row of hair-pins without increasing 30 the complexity of the device in proportion to the increased number of pins mounted upon it. Further objects and advantages of the invention will appear hereinafter.

35 Reference is to be had to the accompanying drawings, in which—

Figure 1 is a front view of a double card showing a preferred embodiment of this invention applied thereto;

40 Fig. 2 is a rear view of the same, the card being turned over one of its vertical edges, and

Fig. 3 is an edge view.

The card is provided along its center if it is 45 a double card, or along the top edge if it is a card for a single row of pins, with two series of equally spaced cuts or slits 10 and 11. These are preferably semi-circular and concentric. Although they have been called 50 semi-circular, the smaller one preferably is continued slightly beyond the diameter of the circle so that it is U-shaped, and the larger is terminated at both ends by flaring extensions, but at any rate whether these 55 details are followed or not, the result is

that there is a substantially semi-circular member or tab 12 integral with the card and connected with or hinged to it along a longitudinal line which is substantially diametrical with respect to the two cuts 10 and 11. This member 12 is capable of being swung out of the plane of the card about its axis as will more readily appear from Fig. 3, leaving a central perforation 13 back of which is a tongue 14 integral with the card of course, and always lying in the plane of it to support the back of the hairpin as will appear.

In alignment with the vertical axis of these curves that have been mentioned above 70 is a single opening near the edge of the card and in the form shown at the two opposite edges. These openings are formed by curved slits 15 which I prefer to call U-shaped, although they can be formed in other shapes and are shown as substantially semi-circular at the bottom with their parallel edges extending considerably beyond the horizontal axis of the circle so that the tongue 16 cut out by them forms a support 80 for the legs of the pins substantially in the plane of the card.

From the bottom of each of these curved slits extends a single offset slit 17. This is central at its top but extends off materially 85 to one side so as to form a flexible tongue 18 that is easily bent for a purpose to be described. It will be obvious that when the card is double as shown the three tongues 16 at the two ends and 14 at the center are 90 in alignment with each other, or their centers are substantially in alignment.

In the use of the card the hair-pin to be mounted is handled at its bow end and one of its legs is slipped through the perforation 13 and then it is turned so as to extend in the direction of the tongue 16 at the opposite edge of the card. The pin is brought on the card so that the ends of both legs touch the card, as shown at the lower left 100 corner of Fig. 1, and then without removing the head or bow end from the opening 13 the legs are slipped to the right over the tongue 18 which they bend down. As soon as they pass under it through the slit 17, 105 into the slit 15 they come together at the right of the end of the slit 17 and the tongue 18 is then free to spring up again into the plane of the card. The legs are then released and the left hand leg naturally 110

moves over to the position shown in most of the pins in Fig. 1 so that it comes behind the tongue 18 and the right hand leg remains behind a similar portion on the right side. The left hand pin in the bottom in Fig. 1 is shown in the act of being slipped in while the left hand end at the top is vacant, no pin being shown.

It will be seen therefore that the pins are very easily slipped into position, particularly on account of the fact that the two legs do not have to be handled separately, which constitutes a material economy in this industry and no matter whether two rows are used as shown or only a single row, the pins are securely held in position. They cannot be dislodged by merely shaking the card in any ordinary way for the reason that even in the absence of the second row the bow portions of the pins do not slip to one side far enough to be dislodged from the perforations 13 and obviously the ends of the legs are very securely held in the position in which they have been placed until the tongue 18 is pressed down intentionally or the pin is ripped off, breaking its paper connections. It is found in practice also that this does not materially bend the cards because the bow parts do not extend through the cards at all and they are supported at the extreme tops by the tongues 14, while the legs are supported by the tongues 16 which are flat and simply lift the lower edge of the card slightly from its general plane.

It will be understood, of course, that when only a single row of pins is to be applied to the card the slits 10 and 11 can be made of smaller diameter than shown and the edge of the card will come adjacent to the upper ends of the slits 11.

Although I have illustrated and described only a single form of the invention, I am aware of the fact that many modifications can be made therein by any person skilled in the art without departing from the scope of the invention as expressed in the claims. Therefore I do not wish to be limited to all the details of construction herein shown and described, but what I do claim is—

1. As an article of manufacture, a mounting for hair-pins having means for holding the bow end of a pin, and an opening for receiving the two legs, said opening having a tongue extending into it from the end beyond which said means is located for supporting the rear surfaces of the legs substantially in the plane of the mounting.

2. As an article of manufacture, a mounting for hair-pins having means for holding the bow end of a pin, and a single opening for receiving the two legs, said opening having a tongue extending into it for supporting the rear surfaces of the legs in the plane of the mounting, and a flexible tongue extend-

ing sidewise beyond said opening to a point 65 near the center thereof and adapted to be pressed back to admit the ends of the legs into said opening.

3. As an article of manufacture, a sheet 70 for holding hair-pins or the like having means for holding the bow part of each pin, and an individual opening through the sheet for receiving the two legs of each pin and limiting their distance apart.

4. As an article of manufacture, a sheet 75 for holding hair-pins or the like having means for holding the bow part of the pin, and a single opening for receiving the two legs, said opening being substantially symmetrical but having a single slit extending 80 away from it at an angle to facilitate entering the ends of the legs therein.

5. As an article of manufacture, a sheet 85 for holding hair-pins or the like having a tab provided with a single perforation therethrough for receiving the extreme bow part of the pin, and a single opening for receiving the two legs.

6. As an article of manufacture, a sheet 90 for holding hair-pins or the like having a perforation therethrough for receiving the bow part of the pin, and a single opening for receiving the two legs, said opening being substantially U-shaped with the curved 95 part at the bottom and having a slit extending from the center of the curved portion thereof at an angle to a line drawn from that point to the center of the first named perforation.

7. As an article of manufacture, a sheet 100 for holding hair-pins or the like having a perforated tab connected to the sheet along a line located longitudinally with respect to the pins for receiving the bow part of the pin, and a single opening for receiving the 105 two legs, said opening being substantially symmetrical but having a single slit extending away from it at an angle to facilitate entering the ends of the legs therein by a sidewise motion.

8. As an article of manufacture, a sheet 110 for holding hair-pins or the like having two concentric perforations forming a substantially semi-circular tab with a tongue between its ends, the tab being adapted to swing away from the plane of the card about a longitudinal axis and providing an opening for receiving the bow part of a hair pin, and a single opening substantially 115 in alignment with said axis for receiving the two legs.

9. As an article of manufacture, a sheet 120 for holding hair-pins or the like having two concentric perforations forming a substantially semi-circular tab with a tongue between its ends, the tab being adapted to swing away from the plane of the card about a longitudinal axis and providing an 125

opening for receiving the bow part of a hair pin, and the tongue constituting a support for the pin in the plane of the sheet.

10. As an article of manufacture, a sheet
5 for holding a double row of hair-pins or the
like having two spaced perforations near
the center for receiving the bow parts of two

pins, and a single opening at each opposite
edge of the sheet for receiving the two legs
of one of said pins. 10

In testimony whereof I have hereunto
affixed my signature.

HARVEY M. OWENS.
